Application December 14, 1935, Serial No. 54,390

24 Claims. (Cl. 178—23)

This invention relates to communication systems and more particularly to synchronous registering controlling systems, one well known form of which is the printing telegraph system, 5 and is applicable for transmission over both line and radio networks.

One object of the present invention is the provision that two timed impulses are employed for all the character representations to be transmitted and received and registered accordingly.

Another object of the present invention is that the usual electromagnetic relays connected directly to the line or through a signal amplifier to transmit and respond to the signal impulses are dispensed with and substituted by substantially inertialess relays having no moving parts.

Another object of the invention is the provision of means whereby it is impossible to transmit or select subsequent character signal impulses before the preceding character impulses have been transmitted.

Still another object is the provision of means whereby but one character selection can be effected at the receiver at one time.

Various other objects and advantages of the invention will be obvious from the following particular description of one form of mechanism embodying the invention or from an inspection of the accompanying drawings; and the invention also constitutes certain new and useful features of construction and combination of parts hereinafter set forth and claimed.

In the drawings:

Fig. 1 shows schematically the circuit arrangement of the transmitting circuit.

Fig. 2 shows the circuit diagram for the receiving circuit.

Fig. 3 shows a modification of the circuit diagrams when the invention is applied to radio transmission.

Fig. 4 shows in part one form of registering or printing transmitting and receiving unit.

Fig. 5 shows a timing chart as applied to the system described.

Briefly and broadly, the present invention comprises a synchronous controlling system in which timed impulses are imparted to a transmission circuit. Two such timed impulses are employed for all the character representations and to effect the corresponding selection of controlling circuits at the receiver. It will be evident from the description to be presented that a number of different circuit selections may be made by employing two signal impulses for each character, the said impulses transmitted at certain particu-

lar timed periods during a predetermined timed interval. Other features and advantages thereof will be obvious as the description progresses.

In accordance with the present invention, in place of the usual electromagnetic relays connected directly to the line, electrical discharge tubes are used and are of a type in which the discharge is started by a momentary application of a signal condition thereto, the discharge continuing independently of the applied signal condition until interrupted by a locally controlled means.

A convenient form of discharge tube for this apparatus may comprise a gas filled thermionic tube of such construction that when the anode is connected to positive battery and a certain potential is applied to the grid, the tube will start and current will flow from the anode to the cathode. As soon as the plate current begins to flow, the grid is instantly surrounded by a sheath of positive ions and has no further effect in controlling the plate circuit. Changing the grid voltage merely changes the thickness of the sheath and has no effect on the potential of the rest of the space. Hence, removal of the grid potential will not stop the plate current once it is started. However, it can readily be stopped by removing the plate voltage. The function of the grid may therefore be likened to a trigger. The amount of power required to start the tube is exceedingly small.

A form of thermionic tube having the characteristics described is the type known commercially as "thyatron" and consists of an envelope containing a low pressure of vapor such as mercury, argon, etc. and a plurality of electrodes consisting of cathode, grid and anode.

In the embodiment shown hereinafter, all the grids of the discharge tubes are maintained at a predetermined negative bias, and adapted so that when the grid bias is sufficiently reduced momentarily, the gas becomes ionized and the anode will draw current until its circuit is broken or the plate potential reduced to a minimum value. The tubes in the present invention are triggered and made to start by means momentarily short circuiting the grid circuit thereby reducing the grid bias sufficiently for the tube to operate.

Another method is suggestive immediately, 50 namely, by impressing a voltage opposing the polarity of the normal grid bias so as to effectively reduce the bias to a value to cause the tube to function. In series with the grid circuit of each tube a resistor of high order may 55

be used to limit the amount of grid current of the tubes. Also shown in the drawings is another resistor shunted by a capacity, the resistor in this case, if used, should be of quite a low order to limit the current flowing in the circuit, the grid tap is then taken at the midpoint of the two resistors. The capacity may be used to prolong the grid impulse allowing the plate potential time to build up and overcome the inductance time lag of the relays. While a preferred manner is shown for controlling the starting of the discharge of the tubes of this general nature, in response to character signals, it is to be understood, of course, that it is not desired to be limited to the particular means shown.

Before proceeding with the description of the transmitting and receiving circuits, it is advisable to set forth briefly one form of a translating or registering unit which may be embodied in the present invention.

For illustrative purposes, this invention is shown as embodying a well known form of translating unit which may be the electromatic typewriter, and hence requires only the following brief description.

Referring to the drawings, and in particular to Fig. 4, in the embodiment illustrated in the drawings, well known means are provided for actuating the type bars (not shown) by power operated devices comprising a power driven roller 10.

A cam 11 is pivoted on one arm of a bell crank lever 12 pivoted in the frame, the other arm of which is operatively connected with one arm of a bell crank lever 13 by means of link 14. The other arm of lever 13 is connected to the type bars (not shown) in a well known manner.

The lever 12 is actuated by the cam 11 when the latter engages the driven roller 10 to be operated thereby. The engagement of the cam 11 with the power roller is controlled by means of the key lever 17 in a manner which will now be described.

The cam 11 is resiliently engaged by a spring-pressed arm 20 which tends to turn it into engagement with the power driven roller or stop 21 on a lever 22 pivoted on the bell crank 12 and normally arranged in the path of a lug on the cam. When the lever 22 swings to move its stop out of the path of the lug, the arm 20 swings the cam into engagement with the power roller to be actuated thereby to swing the bell crank 12 to actuate its connected mechanism.

The lever 22 has an arm 24 which is provided with an offset projection 25 at its end which projects laterally through an opening in the bell crank 12 and engages the bifurcated lower end 26 of an arm 27 of a key lever 17 pivoted on the common rod 28.

It is obvious then that depression of a key lever 17 releases the revolvably mounted cam 11 to engage and be actuated by power roller 10 in turn operating bell crank 12 and its attached links to cause the associated mechanism, such as the key bars and other operating mechanisms, to be operated.

Attached to the key lever 17 is a connecting link 19 extending to a solenoid 18 disposed beneath the keyboard, so that upon energization of the said solenoid the connected key lever is depressed to operate the connected mechanism in the manner just explained.

In addition to actuating the several type bars and connected mechanisms, the revolvably mounted cams are adapted to make and break circuits

which may be employed in the transmitting units, the purpose of which will be understood as the description progresses. Upon release of the cam 11 the ensuing operation thereof causes the contact spring blade 30 by virtue of its attached cam follower roller 31 adapted to engage the cam during its partial revolution, to be urged away from the power roller 10 to close the contacts 33. Since the cam turns exactly one half of a revolution before being arrested, the spring blade 10 30 returns to its normal position as shown in the drawings, by virtue of its own resiliency, thereby restoring the contacts to their normal open position.

It will be understood that the usual number 15 of key bars and power devices with their associated mechanisms are provided, but only one of them is shown for the sake of clearness. It is obvious, therefore, that for a simplex system operation the transmitting unit may comprise the 20 device just described including the cam operated switch arrangement, and for the receiving unit, the device described may be used as shown including the connected solenoids.

Referring now to Fig. 1, one type of circuit 25 which may be employed at the sending station, embodying the double impulse system, will now be described. The contacts 33 representing the various keyboard characterizations and associated with each character key bar in the manner just 30 described are segregated and connected in groups of seven.

Each one of the contact members of the different groups of contacts 33 is connected to a common conductor connecting the said members to 35 individual relays such as 35-8 to 14. It is to be noted that the said group of relays comprises separate pickup or energizing coils and holding windings or coils, the purpose of which will be understood as the description progresses.

Each one of the remaining contact members of the said group of contacts 33 is connected to a corresponding relay winding of the group of relays 35-1 to 7. The other side of the windings of the last mentioned group of relays are connected 45 by a common conductor 36 to ground. The pickup windings of the relays 35-8 to 14 are connected to a common conductor 37 through a normally closed contact 38 to grounded battery 39.

It is evident from the description just set 50 forth that upon the closure of any one of the contacts 33 one of the relays of the group 35-1 to 7 and one of the relays of the group 35-8 to 14 are selected and connected in series with the said source of potential. A specific circuit will 55 now be traced for a particular character selection. Let it be assumed that the key bar (Fig. 4) for the character "A" is depressed to effect the closure of the corresponding contacts 33 (Figs. 1 and 4), grounded battery 39 is then impressed upon the following circuit: through normally closed contacts 38, common conductor 37, pickup or energizing winding of relay 35-8, common conductor 40, the corresponding contacts for character "A" now closed, common conductors 41 and 42, winding of relay 35-2 and common conductor 36 to ground. In this manner, relays 35-2 and 35-8 are energized to close the associated contacts 43 and 44, 45 and 46, respectively.

It is desirable to maintain the particular relay selection until the corresponding character impulses have been impressed upon the transmission network, and secondly to prevent the possible selection and energization of a second group 75

of relays corresponding to another character until the preceding character has been transmitted to the receiving station. One method of effecting this feature is as follows: grounded battery 39 is connected through the normally closed contacts 47, conductor 48, winding of relay 49, common conductors 53 and 51, contacts 43 now closed, winding of relay 35-2 and conductor 36 to ground. The locking circuit just described is established immediately upon the energization of relay 35-2 to maintain the said relay in an operated condition until the character impulses are transmitted to the connected network; similarly relay 35-8 is maintained in an operative condition due to the connection of grounded battery 39 to common conductor 51, contacts 46 now closed, locking or holding winding of relay 35-8 and common conductor 36 to ground.

Connection of grounded battery 39 to winding of relay 49 as just described causes the energization of the said relay to close the associated contacts 52 and 53. Grounded battery 39 is now connected through the winding of relay 54, conductor 55, contacts 52 now closed to ground, energizing relay 54, opening the associated normally closed contacts 38. In this manner, grounded battery 39 is disconnected from common conductor 37 which is connected to the pickup windings of relay 35-8 to 14. It is obvious now that the subsequent selection of relays from the groups 35-1 to 7 and 35-8 to 14 cannot be effected by the closure of any of the contacts 33 until the locking circuits described therefor are broken which does not occur until the character impulses have been impressed upon the transmission network and which will now be described.

A transmitting commutator or distributor 56 is employed to impart particular time values to the character impulses to be transmitted and comprises a solid collecting ring 57 and associated brush 58, a segmented ring 59 comprising a plurality of conducting segments of which there are two main groups, namely, 59-1 to 7 and 59-8 to 14. Two additional segments 59-15 and 59-16 are utilized and the purpose of which will become apparent from the following description. A brush 60 is associated with the segmented ring 59. An insulated ring 61 having two conducting segments, the position of which correspond to conducting segments 59-15 and 16, is included in the distributor 56, a brush 62 is associated therewith. Commutators or distributors 53 are old and well known in printing telegraph systems so that further description thereof is deemed unnecessary. The brushes 58, 60 and 62 are connected together electrically and may be driven in the usual manner by suitable means such as a motor (not shown). In addition thereto conducting rings 63 and 64 are included in the distributor 56 having insulated segments disposed thereon as shown which are positioned so as to be engaged by the associated brushes 65 and 66, respectively, when the brush 60 is positioned between the conducting segments 59-14 and 59-15. As mentioned before, the brushes 58, 60, 62, 65, and 66 are all rotated in unison by suitable means and in the direction as indicated in the figure.

The conducting segments 59-1 to 7 and 59-8 to 14 are associated with contacts of the relays 35-1 to 7 and 35-8 to 14 respectively so that during the proper period in the distributor cycle the timed character designating impulses can be

impressed upon the transmitting circuit. A common conductor is also associated with the said contacts and connected to one side of the line. The other side of the line is connected by conductor 68 to the normally open contacts 69 associated with relay 70 which in turn are connected to the solid conducting ring 57 of the distributor 56. Up to this point, it is seen that character designating impulses cannot be transmitted to the said line until at such time the relay 70 is energized to connect the one side of the line to the said conducting ring 57.

However, relay 70 can be energized only when the relay 49 is energized during the timed interval that the brush 60 engages the conducting segment 59-16, and similarly brush 62 engaging the conducting segment in the insulated ring 61 corresponding to the segment 59-16. The said segment in ring 61 is connected to the grid of the discharge tube 71 and the segment 59-16 is connected to the cathode of said tube through the contacts 53 associated with relay 49. Therefore, it is seen that during the periods when relay 49 is energized and brush 60 engages the conducting segment 59-16 and at the same time brush 62 engages the corresponding segment in ring 61, a circuit is established whereby the bias on the grid of the tube 71 is changed, which in turn is adapted to start or trigger the tube to permit current to flow in the plate circuit thereof.

The plate circuit established at this particular timed interval is as follows: from the positive terminal of battery 72 to one of the brushes 65, solid conducting ring 63, the other brush 66, conductor 73, winding of relay 70, plate of tube 71 to the cathode thereof and to a negative terminal of the battery. In this manner, relay 70 is energized, opening the normally closed contacts 47 and closing contacts 69 to directly connect the line to the conducting ring 57.

The locking circuits described and established through the winding of relay 49 are not broken by virtue of contacts 47 being opened, due to a shunt circuit established through conductor 74, conducting ring 64 and brushes 66 and conductor 75 thereby permitting the grounded battery 39 to energize the said locking circuits.

Consequently, during subsequent engagements of the brush 60 with the segments 59-1 to 7 and 59-8 to 14, a closed line circuit condition is established through the contacts of the energized relays, which for the example chosen, it is remembered, are the relays 35-2 and 35-8, when the brushes 58 and 60 are positioned to engage the particular associated conducting segments 59-2 and 59-8. The circuits established are as follows and in the order described, one side of the line to conductor 67, contacts 44 associated with relay 35-2, conductor 76, segment 59-2, brushes 60 and 58, conducting ring 57, conductor 77, contacts 69 and conductor 68 to the other side of the line to close the said transmitting circuit and which is indicative of a character designating timed impulse.

Similarly, at an interval later during the same cycle, the following closed circuit condition is established to represent another character designating timed impulse, namely, the one side of the line, conductor 67, contact 45 associated with relay 35-8, conductor 78, segment 59-8, brush 60, conducting ring 57, brush 58, conductor 77, contacts 69 and conductor 68 to the other side of the line.

The effect of the momentary closed line conditions will depend upon the particular applica-

tion of the system, if it is proposed to employ the transmitting circuit described in a metallic line network, the closed line condition may be adapted to alter directly the grid bias of the particular discharge tubes in a receiving circuit to record or register the corresponding characters accordingly, and which is the particular embodiment chosen for an example, setting forth the principle of the invention. However, if employed in a radio network or if desired in a line network, the line terminals in Fig. 1 are connected to the terminals marked transmission line circuit in Fig. 3, which will operate the radio signal transmitter to send out an impulse in a well known manner each time the input circuit thereto is closed as described. The receiver is actuated in the usual manner to operate the connected relay closing the associated contacts 81 thereby closing the receiving line circuit which is connected to the line terminals of the receiving system in Fig. 2. As mentioned hereinbefore, the description of the receiving circuit will be effected in the same manner regardless of the type of transmission employed, that as in the example to be described for a metallic line in which case the line terminals of Fig. 1 are connected to the line terminals of Fig. 2 or for radio transmission when the connections of the circuits just described are employed.

Before continuing with the description of the receiving circuit, it is necessary to mention during the timed interval the brushes 58, 60, 62, 65 and 66 are rotated from segment position 59-14 to segment 59-15 the conditioned and operated circuits of the transmitting system are restored to normal. During this said interval, the brushes 66 engage an insulated portion or segment 82 disposed in the conducting ring 64, thereby breaking the locking circuit established through the winding of relay 49 and consequently de-energizing relays 49, 54, 35-2 and 35-8, restoring the said relays to a normal condition to permit subsequent conditioning of the said relays and similar ones upon the depression of any character keys to transmit at a later timed interval the character designating impulses.

Immediately after the breaking of the said locking circuits, brushes 65 engage an insulated portion or segment 83 disposed in the conducting ring 63 to open the plate circuit described and thereby disabling the tube 71 by preventing further flow of plate current. Relay 70 is deenergized, as a result thereof, to open the contacts 69, disconnecting the one side of the line from the conducting ring 57 and closing the contacts 47 thereby completely restoring the transmitting circuit to a normal condition as shown in Fig. 1.

In order to maintain the operation of the distributors at the transmitter and receiving stations in synchronism provision is made to transmit a periodic, single synchronizing or control impulse.

It is readily seen that by closing the switch 85, during the rotation of the distributor brushes, engagement of brush 60 with segment 59-15 and at the same time engagement of brush 62 with the conducting segment disposed in ring 61 corresponding to the segment 59-15 a closed line condition is established directly through the distributor and transmitted similarly as the character impulses, the description of which has just been set forth.

Before proceeding with the description of the receiving circuit proper, it may be well to de-

scribe briefly the synchronizing control circuits which may be employed in the receiving system. Referring now to Fig. 2, a commutator or distributor 95 is shown developed and similar to the transmitting distributor 56, comprising a segmented ring 96 having disposed thereon exactly the same number of conducting segments as the segmented ring 59; a solid conducting ring 98 is connected to one side of the incoming line, and a third conducting ring 100 provided with a limited number of conducting segments, the last mentioned ring used solely for synchronizing purposes. Associated brushes 97, 99 and 101 are rotated by suitable means such as a motor similarly employed for rotating the transmitting distributor brushes and are connected together electrically and cooperate with the said rings 96, 98, and 100 respectively.

Let it be assumed that the synchronizing switch 85 at the transmitter is closed and that no character impulses are transmitted to the lines and that transmitting distributor brushes and the receiving distributor brushes are being rotated substantially in synchronism.

It was just mentioned that with the switch 85 closed at the transmitter, single periodic control or synchronizing impulses are transmitted continuously. The conducting segment 96-15 is positioned similarly in the timed cycle as the segment 59-15, and segment 100-20 corresponds in position to segment 96-15, therefore, it is seen that if the brushes of both distributors are rotating in synchronism, the control pulse transmitted is conducted from one side of the line to conducting ring 98, brushes 99 and 101 to unconnected segment 100-20 permitting the brushes to rotate in synchronism. However, if a phase shift occurs so that the impulse is received on either conducting segment 100-21 or 100-22 representing a slow or fast rotary condition, the corresponding discharge tube 102 is adapted to be operated by the changed bias condition of the associated grid due to the closed line condition, as explained hereinbefore, to start the tube and permit plate current to flow in one of the tubes. The circuit established is as follows: from one side of the line, through common conductor 111 to the cathode of one of the tubes 102, and from the other side of the line connected to conducting ring 98, brushes 99 and 101 to either segment 100-21 or 100-22 to the associated and corresponding grid of one of the tubes 102. The operation of one of the tubes is then effective to energize either the magnet 103 or 104. The energization of magnet 103 is adapted to retard the receiving distributor brushes until synchronism is established. Similarly, the energization of magnet 104 is adapted to step the said brushes ahead to establish substantial synchronous operation thereof.

It is deemed unnecessary to explain and describe further in detail the specific mechanism to be employed to shift the brushes during rotation to establish synchronous operation, since these mechanisms are old and well known in the art, and for a complete description of one form thereof reference may be made to a copending application, Serial No. 684,362, filed August 9, 1933 in which the magnets 35 and 56 thereof correspond to the said magnets 104 and 103, respectively, herein.

Provision is also made to properly phase-in the distributor brushes, for example, upon starting the transmitter and receiver, it is possible that the brushes are out of phase by more than the

angular position of the correcting segments 100-21 and 22 so that the periodic control pulses are conducted to either segments 100-23 or 100-24. Under such conditions it is necessary to open the switch 105 in the plate circuit of the character receiving discharge tubes to prevent faulty operation thereof and to close the phasing-in switch 106 connecting the segments 100-23 and 100-24 to the tubes 102, similarly as segments 100-21 and 100-22 to operate the magnets 104 and 103 as just described, thereby retarding or advancing the brushes until the receiving distributor brushes are operating in synchronism with the transmitting distributor brushes. The control impulse will then be conducted to either segment 100-20 representing exact synchronous operation or to the adjacent segments 100-21 or 22 which as explained will establish the synchronous condition. When this condition is established, switch 106 is opened and switch 105 is closed and the circuit is conditioned for character signal transmission.

It is to be noted that relays 107 and 108 are included in the plate circuits of the tubes 102, the purpose thereof, is evident, namely to disable or discontinue the operation of the discharge tubes 102 upon energization of the said magnets 103 or 104. Relays 107 and 108 are adapted to be slow operating relays, to permit the magnets 103 or 104 to operate and adjust the brushes before the associated relay contacts 109 and 110 are operated to open the plate circuits of the connected discharge tubes 102. Due to this manner of operation the tubes 102 may be operated successively to energize the magnets 103 or 104 successively thereby advancing or retarding the brushes step by step until synchronous operation thereof is obtained.

In the same figure it is noted that one side 40 of the line which corresponds to the side of the line connected to ring 61 in Fig. 1, through common conductor 111 is connected to a plurality of cathodes of the discharge tubes 112-1 to 7 which are of the type described hereinbefore. 45 The other side of the line connected to the solid conducting ring 98 is connected in succession to segments 96-1 to 14 by the associated brushes 99 and 97 respectively.

It is to be noted that the grids of the tubes 50 112-1 to 7 are connected to one conducting segment of each group of segments, for example, the grid of tube 112-1 is connected by conductor 113 to conducting segment 96-1 and 96-8. Similarly, the other tubes are connected in a like 55 manner to the remaining conducting segments. Therefore, it is evident that the character impulses transmitted and represented by the closed line circuit condition are effective to reduce the grid bias of the corresponding tubes 112-1 to 7; 60 of course, depending upon the distributor brush position to determine which one of the tubes is triggered or started to function at the particular timed interval.

The plate circuit of each of the tubes 112 includes a relay of each group of the relays 114-1 to 7 and 115-1 to 7. The anode of each tube is connected directly to one side of the pickup or energizing winding of each of the corresponding 65 relays, the other side or terminal of which is connected separately and individually to a corresponding brush of the group of brushes 116-1 to 14. The said brushes 116 and brushes 117 are adapted to be rotated in synchronism with brushes 97, 99, and 101 of the receiving distributor 70 75. One simple expedient is to have all the

said brushes fixed to the same rotating shaft thereby insuring unison in operation therebetween. The brushes 117 engage solid conducting rings 118, whereas the individual brushes 116-1 to 14 engage short conducting segments 119-1 to 14 which are interconnected and staggered as shown. The remaining portion of the collecting rings are insulated, the purpose of which will be understood presently.

Referring also to Fig. 5, a chart shows the 10 relative positions of the conducting segments 119-1 to 14 with respect to the conducting segments of the distributor segmented ring. It is seen that the brushes 116-1 to 14 will begin to engage the corresponding conducting segments 119-1 to 14 at exactly the same moment in the timed cycle that the receiving distributing brush 97 engages the conducting segments 96-1 to 14. It will now be apparent that the brushes 116 15 engaging the associated segments 119 will control the selection of the particular relay of the group of relays 114 and 115 associated with the 20 anodes of the tubes 112-1 to 7.

To continue with the assumed example for the character "A" which is represented by character 25 designating impulses at the "2" and "8" particular timed periods during the predetermined timed interval corresponding to a complete distributor cycle. Therefore at these particular 30 timed intervals the following circuits are established and in the order described: The closed line circuit condition, while the brush 97 engages segment 96-2, changes or reduces the grid bias 35 on tube 112-2 to cause the said tube to operate. The specific circuit for effecting this condition 40 is from one side of the line to conducting ring 98, conducting segment 96-2, common conductor 125 to grid of tube 112-2, the other side of the line is connected directly to the cathode of said tube by conductor 111. The change of the bias 45 condition on the said grid permits the tube 112-2 to function as follows: Current flows in the plate circuit which comprises the plate of tube 112-2, pickup or energizing winding of relay 114-2, conductor 126, brush 116-2, segment 119-2 (it 50 is understood that at this particular timed interval brush 116-2 is engaging segment 119-2) solid conducting ring 118, brush 117 to the positive terminal of the "B" battery. The negative 55 terminal of the said "B" battery is connected directly to the cathode of tube 112-2, thus completing the plate circuit and due to the current flow therein relay 114-2 is energized. The segment 119-2, similarly as all the segments 119-1 to 14, is of such length so as to permit the energization and lockup of the associated relays included in the circuits, which for this particular 60 circuit described is relay 114-2.

It is understood that upon the energization of relay 114-2 or any of the other relays 114-1 to 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

lay 114-1, conductor 135, brush 136, conducting rings 137 and 138 to ground, locking the said relay 114-2. Associated with relay 114-2, and similarly with all the relays 114-1 to 7, are a plurality of normally open contacts 148-1 to 7, which are closed upon energization of the associated relay winding and maintained in a closed position due to the established locking circuit maintaining the locking winding energized. The locking windings of the relays 114-1 to 7 once energized remain so for the major portion of the cycle. Reference should be made to Fig. 5 which shows relatively the length of time or the timed interval of the entire cycle that the ring 137 is connected to ground to maintain the locking circuits. Brush 136 is rotated in synchronism with the group of brushes 116-1 to 14.

It is also to be noted that due to the contact arrangement of relays 114-1 to 7, energization of any one of the said relays deenergizes or opens the locking circuit of any of the other relays. In this manner it is impossible to energize more than one of the relays at one time and thus prevent any possible faulty registration of characters or the selection of more than one operating instrumentality.

The second impulse or closed circuit condition is received when the distributor brush 97 is engaging the conducting segment 98-8 and at this particular timed period the grid bias of the tube 112-1 is changed to permit operation of the said tube. Due to the position at this moment of the brushes 116, the energized plate circuit is as follows: from plate of tube 112-1, to conductor 141, pickup or energizing winding of relay 115-1, conductor 142, brush 116-8, conducting segment 119-8 now engaged by said brush, common connected ring 118, brush 117 to the positive terminal of "B" battery. The negative of the said "B" battery is connected directly to the cathode of tube 112-1. The flow of plate current thereby energizes relay 115-1 to permit the following locking circuit to be established, from grounded battery 131, current passes through conductor 132 to one terminal of the locking winding of relay 115-1, the other terminal thereof is connected to contact 146 now closed, conductor 135 to brush 136, conducting rings 137 and 138 to ground. Due to the length of the conducting portion of the segment 119-8, the plate circuit just described is broken once the said locking circuit is established. It is to be noted that the contact arrangement of the relays 115-1 to 7 are such that the energization of one relay interrupts or opens the locking circuit for any of the other relays and in this manner prevents more than one of the said relays to be operated at the same time.

Energization of relay 115-1 also causes the normally open contact 146 to be closed to connect ground through the common conductor 147, contact 146, conductor 148 to a group of solenoids 18. The said group includes solenoids for the operating instrumentalities for the character representations "SP", "A", "Z", "TAB", "Q", "2", and "W". However, it is to be noted that the other terminals of the solenoids all are connected to an open contact with the exception of the "A" solenoid which is connected to contact 148-7 now closed due to the energization of relay 114-2. Thus it has been shown how a character selection is made by the present system. It is obvious that any of the other characters designated can be selected in a like and similar manner and that further description thereof is not deemed necessary.

Now that the character operating or controlling means, namely the solenoid 18, has been selected, an operating impulse is impressed upon the solenoid circuit to energize it and cause the connected mechanism to register the corresponding character. This operating impulse may be transmitted any time in the cycle after the distributor brushes have engaged all the tube conducting segments 98-1 to 14. For example, referring to Fig. 5, the segment 158 indicates a suitable period during the cycle to transmit the solenoid impulse and is effected as follows: grounded battery 151 connected directly to a solid conducting ring 152 is in turn connected to conducting segment 158 disposed in an insulated ring 153. Brush 154 rotated in synchronism with brushes 116-1 to 14 and now engages the conducting segment 158 to permit current to pass from the said battery through conductor 155, closed contact 148-7, solenoid 18 for the character instrumentality for "A", conductor 148, contact 146 now closed, and conductor 147 to ground.

Energization of solenoid 18 causes for example the character "A" key bar of the translating unit described hereinbefore to be depressed, thereby releasing the cam unit and causing the "A" type bar to be operated recording the said character.

Immediately upon energization of the said solenoid or any of the similar solenoids 18, and operation of the said connected mechanism, brush 154 engages an insulated section of the ring 153 for the remaining period of a complete cycle. Similarly, brush 136 engages an insulated section disposed in conducting ring 137 for a brief moment sufficient to interrupt and break the locking circuits established for the relays of the group of relays 114 and 115, namely relays 114-2 and 115-1, thus restoring the said relays to a normal condition as shown in the figure. This completes the description for one cycle of operation of the system and it is obvious how further and other selections may be initiated and completed during subsequent cycles of operation of the system.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a communication system of the character described, means to transmit character signals, including means to initiate two variably timed impulses having similar polarity characteristics for all characters, means to receive said impulses successively, and means to select controlling circuits corresponding to the received signals.

2. In a communication system, means to initiate a plurality of impulses representing various characterizations, including means whereby all of said characterizations are represented by the same number of impulses having similar polarity characteristics, means to impart different time values to the character impulses, and means to transmit said timed impulses in succession.

3. In a synchronous communication system of the character described, means to transmit a plurality of impulses representing various charac-

terizations including control means to impart different time values to the said impulses, means including means operated in timed relationship with said control means to receive said impulses successively, a plurality of controlling circuits, means associated with said receiving means controlled by one of the impulses to select a predetermined number of circuits from said plurality of circuits, and means controlled by another of said impulses to effect a selection of a single circuit from the said predetermined number of circuits.

4. In a synchronous communication system of the character described, means to transmit character signals, including means to initiate a similar number of variably timed impulses for all the characters, means including means operated in timed relationship with said transmitting means to receive said impulses successively, a plurality of circuits, means controlled by one of said signal impulses to select a predetermined number of circuits from said plurality due to a particular timed value imparted thereto and means controlled by another impulse at a later timed interval to effect a selection of a single circuit from the said predetermined number of circuits.

5. A communication system comprising means to transmit a plurality of impulses during a predetermined timed interval including means to impart different and particular time values to the impulses transmitted during the said timed interval, a plurality of circuits, means including means operated in timed relationship with said transmitting means to receive said timed impulses including means whereby one of the timed impulses effects a selection of a predetermined number of circuits from said plurality of circuits, and means controlled by another of the timed impulses to effect a final circuit selection from the said predetermined number of circuits.

40 6. A communication system comprising a plurality of controlling circuits, means to transmit a plurality of differently timed impulses during a predetermined timed interval, means including means operated in timed relationship with said transmitting means to receive said impulses during said timed interval and means controlled by one of said impulses received to initiate a selection of a particular circuit from said plurality of circuits and means controlled by another of said impulses to complete the selection of the said particular circuit.

7. In a communication system, means comprising a plurality of operable instrumentalities to effect a character selection, circuit control means connected in cascade controlled by a selected instrumentality so as to be conditioned by the said instrumentality to maintain said character selection, and means to transmit character impulses at particular timed intervals in accordance with the said conditioned means.

60 8. In a communication system, means comprising a plurality of operable instrumentalities to effect a character selection, relay means controlled by a selected instrumentality to be conditioned by the selected instrumentality to maintain said character selection, means to transmit character impulses at particular timed intervals in accordance with the said selection and conditioned means, and means preventing another selection to be effected during the timed interval a previous selection is maintained by said conditioned means.

9. In a communication system, means comprising a plurality of operable instrumentalities to effect a character selection, relay means con-

trolled by a selected instrumentality to be conditioned thereby to maintain said character selection, means to transmit character impulses at particular timed periods in accordance with the said conditioned means during a predetermined transmission cycle, and means to restore the said conditioned means to a normal condition upon completion of the said transmission cycle.

5 10. In a communication system of the character described, means to transmit a plurality of impulses representing various characterizations including means to impart different time values to the said impulses, means including means operated in timed relationship with said transmitting means to receive said timed impulses, a plurality of controlling circuits, means associated with said receiving means to select a particular circuit from said plurality in accordance with the received impulses, and means to prevent a further selection from said plurality of circuits upon the selection of the said particular circuit.

15 11. In a communication system of the character described, means to transmit a plurality of impulses representing various characterizations including means to impart different time values to the said impulses, means including means operated in timed relationship with said transmitting means to receive said timed impulses, circuit selecting means certain of which are operated by said received impulses and means to prevent the operation of the remaining of said circuit selecting means during the particular interval the said certain selecting means remain operated.

20 12. In a synchronous communication system of the character described, means to transmit character signals, including means to initiate a similar number of variably timed impulses for all the characters, means including means operated in timed relationship with said transmitting means to receive said impulses successively, circuit selecting means and controlling means therefor, said controlling means operated by the said impulses received and adapted to maintain the said circuit selecting means operative beyond the period of application of the said impulses.

25 13. In a communication system of the character described, means to receive character signals comprising a plurality of variably timed impulses, circuit selecting means and controlling means therefor, said controlling means responsive to one of said timed impulses to operate said circuit selecting means effecting a selection of certain particular circuits and including means so that upon reception of another of said timed impulses the same said controlling means is effective to control the selection of certain other and different circuits.

30 14. The invention set forth in claim 13 in which the said controlling means is adapted to maintain the said circuit selecting means operative beyond the period of application of the said impulses.

35 15. A communication system comprising a thermionic device of the type described having input and output circuits, said thermionic device being characterized by continued operation unaffected by grid potential after starting, means to condition the said input circuit at a particular and similar period in each transmission cycle rendering the said device operative, a transmission circuit, and means in the said output circuit controlled whereby signal conditions may be applied to the said transmission circuit.

40 16. The invention set forth in claim 15 including means to render said thermionic device in-

- operative upon completion of the application of the said signal conditions to the said transmission circuit.
17. In a communication system, means to transmit character signals comprising two or more impulses, including means whereby each signal for all characters comprises the same number of successively timed impulses, means to transmit a single periodic control signal, said signals transmitted during a predetermined transmission cycle, means to receive said timed impulses during the said cycle, an indicating device operated by and in accordance with the character signals and means controlled by said periodic signals.
18. In a communication system, means to transmit character signals, including means whereby each signal for all characters comprises two impulses, means to transmit single, periodic control signals, distributing means to impart particular time values to said impulses, means including distributing means adapted to operate in timed relationship with the first mentioned distributing means to receive said timed signal impulses, an indicating device operated by and in accordance with said character signals received, and means to maintain the operation of the said distributing means in the said timed relationship and controlled by said periodic signals.
19. The invention set forth in claim 18 in which the means controlled by said periodic signals includes a thermionic device of the type described having input and output circuits, said device being characterized by continued operation unaffected by grid potential after starting, including means whereby the said input circuits are conditioned by the periodic signals and the said output circuit adapted to control the operation of said distributing means.
20. In a communication system, means to transmit aperiodic character signals and periodic control signals, rotary distributor means to impart particular time values to said impulses, means to receive said timed impulses including rotary distributor means and control means to operate it in timed relationship with the first mentioned rotary means, an indicating device operated by and in accordance with said character signals received, a thermionic device of the type described having input and output circuits, said device being characterized by continued operation unaffected by grid potential after starting, including means whereby the said input circuit is conditioned by the said periodic signals to start the device and means in said output cir-

cuit to control the said control means to operate the said distributors in timed relationship, and means to receive the said periodic control signal at any time to control the said thermionic device.

21. In a communication system, means to transmit character signals, including means whereby each signal for all characters comprises the same number of timed impulses, means to receive said timed impulses including thermionic devices of the type described having input and output circuits, said devices being characterized by continued operation unaffected by grid potential after starting, the said input circuits conditioned by the said impulses to start the devices and circuit selection means operated by the said output circuits, means to render the operated devices inoperative, and means to maintain the circuit selection means operated after the said devices have been rendered inoperative.
22. In a communication system of the character described, means to transmit character signals comprising the same number of variably timed impulses having similar polarity characteristics, means to receive said timed impulses, a plurality of circuits, means to select particular circuits from said plurality in accordance with the said received impulses, and means to energize the selected circuits.

23. In a communication system, means to transmit character signals, including means whereby each signal comprises variably timed impulses transmitted during a predetermined transmission cycle, means including means operated in timed relationship with the said transmitting means to receive said timed impulses during the said cycle, a plurality of circuits, means to select particular circuits from said plurality in accordance with the said received impulses, and means to energize said selected circuits at a predetermined period in said cycle.

24. In a communication system, means to receive character signals during a predetermined transmission cycle, said signals comprising the same number of variably timed impulses for each character, a plurality of circuits, means including means operated in timed relationship with said character signals received to select particular circuits from said plurality in accordance with the said received signals, said last named means adapted to be conditioned to maintain the said selection beyond the period of application of said signals, means to energize said selected circuits, and means to restore said conditioned circuits to normal upon energization of the selected circuits.

CHARLES R. DOTY.
